US00D912209S

(12) **United States Design Patent** (10) Patent No.: **US D912,209 S**
Liu (45) Date of Patent: **** Mar. 2, 2021**

(54) **BASIN MIXER**

(71) Applicant: **Phoenix Industries Pty Ltd**, Bayswater (AU)

D575,848 S 8/2008 Kirar
D577,418 S 9/2008 Lammel
D580,525 S 11/2008 Citterio

(Continued)

(72) Inventor: **Ban Hsi Liu**, Bayswater (AU)

FOREIGN PATENT DOCUMENTS

(73) Assignee: **Phoenix Industries Pty Ltd.**, Bayswater (AU)

AU 308198 7/2006
AU 308199 7/2006

(Continued)

(**) Term: **15 Years**

(21) Appl. No.: **29/678,503**

(22) Filed: **Jan. 29, 2019**

(30) **Foreign Application Priority Data**

Jul. 30, 2018 (AU) 201814524
(51) LOC (13) Cl. 23-01
(52) U.S. Cl. USPC D23/238
(58) **Field of Classification Search**
USPC D23/238-242, 255
CPC E03C 1/04; F16K 31/04
See application file for complete search history.

Primary Examiner — Barbara Fox

Assistant Examiner — Jamaal Rasheed

(74) Attorney, Agent, or Firm — Womble Bond Dickinson (US) LLP

(57) **CLAIM**

The ornamental design for a basin mixer, as shown and described.

DESCRIPTION

FIG. 1 is a perspective view of a basin mixer according to my new design;

FIG. 2 is a right side view thereof, the left side view being a mirror image thereof;

FIG. 3 is a top view thereof;

FIG. 4 is a bottom view thereof;

FIG. 5 is a front view thereof; and,

FIG. 6 is a rear view thereof.

The evenly-spaced broken lines in the figures represent portions of the basin mixer that form no part of the claimed design.

1 Claim, 2 Drawing Sheets
